UNITED STATES PATENT OFFICE.

WILLIAM CLARK, OF SHAKER HEIGHTS VILLAGE, OHIO.

MACHINE FOR HEADING UP BARRELS.

Application filed November 25, 1921. Serial No. 517,475.

To all whom it may concern:

Be it known that I, WILLIAM CLARK, a citizen of the United States, residing at Shaker Heights Village, in the county of 5 Cuyahoga and State of Ohio, have invented a new and useful Machine for Heading Up Barrels, of which the following is a specification.

This invention relates to improvements in 10 machines for heading up barrels, and pertains more especially to a machine adapted to be employed in heading up an upright open barrel comprising staves in the formation of its body to the upper portion of 15 which a barrel-head and a head-*hoop* are to be applied.

My improved machine comprises a cable 20 for encircling the upper portion of said barrel preparatory to driving said hoop into place, a substantially vertically movable slide suitably spaced upwardly from the barrel-receiving base, means for actuating the slide, a hoop-driving head supported from and movable with the slide and having 25 a movement independent of the slide and adapted, when it is in position at one end of its independent movement in the upper position of the slide, not only to descend with the slide but to drive the aforesaid 30 hoop into place during the descent of the slide, and means whereby the aforesaid cable, upon placing it into its barrel-encircling position preparatory to the descent of the 35 slide, is tightened, during the descent of the slide and before the hoop-driving operation, in relation to the staves of the barrel so as to tighten the staves in relation to the aforesaid barrel-head.

One object of this invention is to provide 40 my improved machine with a hoop-driving head which has a substantially horizontal movement independent of the slide supporting said head and is manually movable out of the way of an upright open barrel to be placed in the required position for receiving a barrel-head and the head-*hoop* to be driven into place.

Another object is to have the hoop-driving head positively and accurately drive the head-*hoop* into place during the descent of the slide.

Another object is to have the machine comprise efficient and reliable means whereby, during the descent of the slide and before driving the head-*hoop* into place, the

barrel-encircling cable is tightened in relation to the barrel-staves so as to tighten the staves in relation to the barrel-head.

Another object is to render a machine of the character indicated simple, strong and durable in construction and reliable in its operation, and to facilitate the operations to be performed by the movable parts of the machine.

With these objects in view, and to attain 65 any other object hereinafter appearing, this invention consists in certain features of construction, and combinations and relative arrangements of parts, hereinafter described in this specification, pointed out in the 70 claims, and illustrated in the accompanying drawings.

In said drawings, Figure 1 is a front view, partly in section, of my improved machine for heading up barrels. Fig. 2 is a central 75 section taken along the line 2—2 in Fig. 1. Fig. 3 is a horizontal section taken along the line 3—3 in Fig. 2. Figs. 4 and 5 are vertical sections taken along the line 4—4 and line 5—5, respectively, in Fig. 2, looking 80 rearwardly. Fig. 6 is a horizontal section taken along the line 6—6 in Fig. 1, except that Fig. 6 shows an open barrel mounted on the base of the machine. Fig. 7 is a view similar to Fig. 6, except that Fig. 7 shows 85 the barrel accurately positioned on said base and shows the upper end of the barrel supplied with a head and head-*hoop* which is to be driven into place. Fig. 8 is a view similar to Fig. 2, except that Fig. 8 shows 90 the barrel accurately positioned on said base and shows a head-*hoop* in position to be 95 driven into place. Fig. 9 shows a portion of Fig. 8, but in Fig. 9 the hoop-driving head is shown lowered into proximity to the head-*hoop* to be driven into place during the descent of the hereinbefore mentioned slide. 100 Fig. 10 is a vertical section taken along the line 10—10 in Fig. 8, looking rearwardly. Fig. 11 is a vertical section taken along the line 11—11 in Fig. 9, looking rearwardly. Fig. 12 is a view similar to but drawn on a 105 larger scale than Fig. 9, except that the head-*hoop* is shown as driven into place in Fig. 12. Fig. 13 is a vertical section taken along the line 13—13 in Fig. 12. Portions are broken away in the drawings to reduce 110

their size and to more clearly show the construction, and Figs. 12 and 13 are drawn on a larger scale than the other figures.

Referring to said drawings, 15 (see Figs. 1, 2 and 3) indicates two laterally spaced and oppositely arranged vertical metal standards which are mounted on and secured to and rigid with a horizontal metal plate 16 having the dimensions required to render it capable of serving as a base on which a barrel, to which a head and a head-hoop are to be applied, may be mounted on end, and said standards are far enough apart to permit said barrel to be placed in the space between the lower portions of the standards and in position to receive said head and said hoop from above. Said standards extend a suitable distance above the base 16 and are tied together at their upper ends by a metal cross-bar 17 secured to the standards in any approved manner. The upper portion of each standard 15 is provided, at the inner side of the standard, with a laterally and inwardly projecting and guideway-forming vertical rib 18, and the ribs 18 of the standards are directly opposite and parallel. The rib 18 of each standard engages a groove 19 formed in and extending vertically through the adjacent end portion of a substantially vertically movable slide 20 which extends between the upper end portions of the standards and is supported from a substantially vertical screw 21 employed in actuating said slide. Said screw is arranged centrally between the ends of and threaded into and extends through the slide 20 and also extends through and has lateral bearing in the cross-bar 17 from which said screw is supported. Said screw is provided, next the under side of the bar 17, with an upwardly facing annular shoulder 22 which cooperates with said bar in preventing upward endwise movement of the screw. Arranged over and resting on the central portion of the bar 17 is a bevel-gear 23 which is operatively mounted on the screw 21 in any approved manner. The screw 21 extends above the gear 23, and a nut 25 is threaded onto said screw next above said gear and cooperates with said gear in preventing downward endwise movement of the screw. It will be observed therefore that the screw 21 is held against endwise movement during the rotation of the screw and that the slide 20 is lowered or elevated according as said screw is rotated in the one or the other direction. The bevel-gear 23 constitutes a member of the mechanism employed in operating the screw 21 and meshes with a bevel-pinion 26 operatively mounted on a horizontal shaft 27 which is spaced substantially vertically upwardly from and parallel with the cross-bar 17 and rotated in

any approved manner in the one direction or the other as may be required. Means for rotating a shaft a predetermined extent in the one or the other direction, and means for controlling the operation of screw-rotating mechanism, are too well known in the art to require illustration and description in this specification.

The slide 20 (see Figs. 2 and 3) has a rearwardly projecting horizontal frame 29 hereinafter referred to and is provided, at its under side, with two substantially horizontal laterally spaced metal bars 30 which are arranged between the standards 15 and substantially parallel and substantially at a right angle to the travel of the slide and extend rearwardly from under the forward portion of the slide a suitable distance. Said bars 30 are secured to the slide 20 by any suitable means such, for instance, as bolts 31, shown in dotted lines in Figs. 1 and 3 and in solid lines in Figs. 10, 11 and 13. Each of the bars 30 (see Figs. 1, 2, 3 and 4) is provided at the bottom with a laterally and inwardly projecting substantially horizontal flange 32 which extends longitudinally of the bar and therefore projects toward and is spaced from the corresponding flange of the other of said bars. The flanges 32 of the bars 30 form a track from which the hoop-driving head of my improved machine is supported, and said head has an interiorly chambered body 33 and has its hoop-engageable face formed by a substantially horizontal metal plate 34 secured to and rigid with said body, and 35 indicates the interior chamber of said body. The body 33 of the hoop-driving head extends between the track-forming flanges 32 of the bars 30 and is provided with two rollers 36 arranged at opposite sides respectively of said body and each resting on the adjacent flange 32. It will be observed therefore that the slide 20 forms a movable support for and extends over the hoop-driving head and is provided with a track arranged at the under side and transversely of the slide and extends rearwardly from within the space between the standards 15, and that said head has an independent movement endwise of the track-forming flanges 32, and consequently from its rearward and inoperative position shown in Figs. 2 and 3 into its forward position shown in Fig. 8, and vice versa, and the relative arrangement of the parts is such that the tops of the rollers 36 are slightly lower than the top of the body 33 of the hoop-driving head, and that said body, when the slide 20 is in its upper position shown in Figs. 1, 2, and 8, is somewhat spaced downwardly from the slide. Also, the body 33 is provided, at the front of its lower portion, with a handle 37 for convenience in man-

ually shifting the hoop-driving head end-
wise of the track-forming flanges 32.

On the flange 32 of each bar 30 (see Figs. 1, 2, 3, 4, 8, 9 and 12) are mounted two 5 stop-forming members 38 and 39 arranged at the forward end and rearward end respectively of and secured in any approved manner to said flange. The length of the bars 30 and the relative arrangement of the 10 parts are such that the rollers 36 of the hoop-driving head abut against the rearward stop-forming members 39, or against the forward stop-forming members 38, according as said head is in its rearward position 15 shown in Figs. 1, 2 and 3, or in its forward position shown in Figs. 8 and 9; that said head, in its rearward position, is rearwardly out of the way of the barrel-receiving space between the lower portions of the standards 20 15 and, in its forward position, is over said space,—and that said head, when it is at the forward end of its independent movement in the upper position of the slide, is adapted to be lowered the extent required to drive a 25 head-hoop into place during the required descent of the slide, and obviously the lowered hoop-driving head, during the return of the lowered slide into its upper position, is elevated from a head-hoop driven into 30 place by said head.

Rearward movement of the barrel on the platform-forming base 16 (see Figs. 1, 2 and 6) is limited by the rearwardly curved central portion of a metal bar which has opposite 35 end portions 42 thereof secured to opposite standards 15 respectively, and two barrel-guiding and barrel-positioning members 43 are pivoted vertically, as at 45, to said bar at the inner end of opposite end 40 portions respectively of the bar and extend forwardly from their axes and circumferentially of opposite sides respectively of the barrel-receiving space between the lower portions of the standards 15. Each barrel- 45 positioning member 43 has a laterally and inwardly projecting arm 46 rearward of the axis of said barrel-positioning member, and the arms 46 of said members 43 project toward each other and are spaced laterally at 50 their free ends. Fig. 6 shows an upright open wooden barrel B comprising staves in the formation of its body and mounted on the base 16 and arranged between the barrel-positioning members 43, and the relative arrangement of the parts is such that the abutment-forming member 41 and the arms 46 are arranged at the rear of the upper portion 55 of the barrel-receiving space, and that the barrel, during shifting of the barrel 50 from the position shown in Fig. 6 rearwardly into the position shown in Figs. 7 and 8, and consequently against the abutment-member 41, swings said arms rearwardly and thereby actuates the barrel-positioning members 43 into a position in

which said members 43 embrace the barrel and insure accurate positioning of the barrel on the base 16.

Rearward of the lower end of each standard 15 (see Figs. 2, 3 and 6) is a metal 70 plate 47 mounted on the base 16 to which said plate is rigidly secured in any approved manner, and said plate has two upwardly projecting flanges 48 formed at the rear end and forward end respectively of the plate, 75 and a horizontal pivotal pin 49, arranged substantially at a right angle to the axes of the rollers 36 of the hoop-driving head, has bearing in said flanges and forms the fulcrum of a lever 50 which is arranged rearward of the adjacent standard 15 and extends from said pin upwardly to a point 80 above the slide 20. A coiled spring 51 (see Fig. 10) extends between the upper ends of the levers 50 and is attached to said levers 85 in any approved manner.

The screw 21 extends below the slide 20 in the upper position of the slide, and a flexible cable is arranged under said slide and has its central portion in the form of 90 a loop 53 which (see Figs. 1 and 2) leans against the rear side of the lower end of said screw, and opposite end portions 54 and 55 of said cable cross each other adjacent the free ends of the arms 46. Said cable 95 (see Figs. 1, 5 and 6) has its end portion 54, which extends from the left-hand side of the loop 53, leading toward and operatively connected with the lever 50 behind the standard 15 at the left-hand side of the 100 machine, and the cable has its opposite end portion 55, which extends from the right-hand side of said loop, leading toward and operatively connected with the lever 50 behind the standard 15 at the right-hand side 105 of the machine. Preferably the operative connection between each end portion of said cable and the lever 50 toward which said end portion of the cable leads is shown as comprising a substantially horizontal eye-bolt 110 arranged substantially at a right angle to the axis of said lever and having its eye 57 opposite and spaced from the laterally inwardly facing side of said lever and attached in any approved manner to said end portion of the cable, and said bolt has its shank 58 extending loosely through the lever and beyond the laterally outwardly facing side of the lever, and a nut 59 is threaded onto said shank at and abuts 115 against the last-mentioned side of the lever so that any lateral outward movement of the lever will result in the exertion of pressure by the lever against the inner end face of said nut and thereby pull on the connected end portion of the cable. Obviously the 120 barrel-encircling cable is tightened in relation to the barrel by simultaneously swinging the levers 50 laterally outwardly.

The barrel B, shown mounted on the 130

base 16 in Fig. 6, has already been headed up at one end which is the lower end of said barrel, and 60 indicates the lower head of said barrel. Upon the application, to 5 said barrel, of the loop 53 of the cable as required to cause said loop to encircle the barrel after properly positioning the barrel on the base 16, as shown in Fig. 7, the upper head 61 of the barrel is inserted into 10 place and the head-clip 62 is mounted on the upper end of the barrel and in position to be driven downwardly into place, and thereupon the hoop-driving head while the slide 20 is or remains in its upper position, 15 is actuated forwardly from its rearward and inoperative position, shown in Figs. 2 and 3, into its forward position shown in Fig. 8, whereupon the screw 21 is rotated in the direction and to the extent required 20 to lower the slide far enough to result in driving said hoop 62 into place as shown in Fig. 12. The body 33 of the hoop-driving head (see Figs. 1, 2, 3 and 8) is provided, at the front and top thereof, with 25 a slot 35 arranged as required to permit said body to clear the screw 21 during movement of the hoop-driving head from its rearward position shown in Figs 1 and 3 into its forward position shown in Fig. 8. 30 Fig. 9 shows the hoop-driving head as having come into close proximity to but not yet into contact with the head-clip 62 during and before the completion of the descent of the slide, and obviously the hoop- 35 driving head, upon coming into engagement with said hoop during said descent of the slide, will momentarily cease to descend until the slide during its said descent abuts against the top of the body 33 of the hoop- 40 driving head and drives the hoop-driving head downwardly to complete the downward movement of the hoop-driving head so as to result in the driving of said hoop into place as shown in Fig. 12, and, of course, 45 the rotation of the screw 21 is arrested and reversed in any approved manner as soon as said hoop has been driven into place. 50 The upper portion of each lever 50 (see Figs. 1 and 10) is provided, at the laterally inwardly facing side of the lever, with an upwardly and laterally inwardly facing incline 63 which terminates at its lower end in a laterally inwardly facing surface 64 extending downwardly from the lower end 55 of said incline and formed on said lever at said side of the lever. The rearwardly projecting frame or member 29 of the slide 20 (see Figs. 2, 3, 8, 9, 10, 11, 12 and 13) is provided, adjacent each lever 50, with a substantially horizontal roller 65 which is 60 substantially parallel with the axis of the lever, and the relative arrangement of the parts is such that said roller, in the upper position of the slide engages the incline 63 on said lever as shown in Figs. 1 and 10 and 65 cooperates with said incline in actuating said lever laterally outwardly during the descent of the slide, and that said roller, during said descent of the slide, comes into engagement with the surface 64 of said lever, as shown in Fig. 11, before the slide has come into its lower position shown in Fig. 13, and that said roller is in engagement with said surface 64 in the last-mentioned position of the slide. Preferably 70 the levers 50 in their inner position, shown in Figs. 1 and 10, tip somewhat toward each other so as to assist the spring 51 in the retention of the levers in contact with the rollers 65, and the relative arrangement of 75 the parts is such that in said position of the levers their surfaces 64 diverge somewhat downwardly, and that in the outer position of the levers, as shown in Figs. 11 and 13, said surfaces are substantially 80 vertical. The loop 53 of the cable, upon its application to a barrel as shown in Figs. 7 and 8, is loose in relation to the barrel. Obviously the rollers 65 carried by the slide 20 and the inclines 63 on the levers 90 50 constitute means whereby the levers are simultaneously actuated laterally outwardly, against the action of the spring 51, during downward travel of the slide, and obviously the loop 53 of the cable is reduced 95 in size diametrically during said actuation of the levers so that the barrel-encircling cable is tightened as required in relation to the barrel-staves so as to tighten said staves in relation to the barrel-head 61 and 100 reliably secure said head in place, as shown in Fig. 9, before the hoop-driving head has come into engagement with the head-clip 62 during the descent of the slide. 105 By the construction hereinbefore described it will be observed that the slide 20 is only adapted to exert pressure on the top of the body 33 of the hoop-driving head after said head has come into engagement with the head-clip 62 during the descent of 110 the slide, that as the rollers 65 are wholly below said top of said body and as said top is spaced downwardly from the slide there is no liability of strain on or injury to said rollers, or on the means attaching the rollers to said body, during the exertion 115 of pressure on said body by the slide in driving said hoop into place, and that, in fact, said rollers are spaced from the flanges 32 as well as from the slide upon driving 120 said hoop into place as shown in Fig. 13. 125 Each lever (see Figs. 1 and 2) is preferably provided, at a point below the guide-rib 18 formed on the adjacent standard 15, with a forwardly projecting rigid arm or member 69 which extends opposite the laterally inwardly facing side of said standard and is spaced from said standard in the inner position of the lever far enough 130 to avoid interference with the required out-

ward movement of the lever during the cable-tightening operation of the levers, but the members 69 of the levers are arranged to cooperate with the standards 15 to form stops for preventing material additional outward movement of the levers, so that when the machine is idle, or at any other time there is no liability of the levers moving outwardly far enough to unduly strain the spring 51.

What I claim is:

1. A barrel heading up machine comprising a movable head for driving a head-hoop into place, a substantially vertically movable support for and extending over said head, and means for actuating said support, said head being movable with said support and having a movement independent of said support from a rearward and inoperative position into a forward and operative position and vice versa and, when it is in its forward position in the upper position of said support, being arranged to be lowered to drive the head-hoop into place during the required downward movement of said support.

2. A machine of the character indicated comprising a head for driving a head-hoop into place, a substantially vertically movable support for and extending over the hoop-driving head, and means for actuating said support, said head being movable with said support and having a substantially horizontal movement independent of said support and being in position to make its hoop-driving downward movement during the descent of said support when said head is at the required end of its independent movement in the upper position of said support.

3. A machine of the character indicated comprising two spaced standards between the lower portions of which is adapted to be mounted an upright open barrel onto the upper end of which a head-hoop is to be driven, a substantially vertically movable slide extending between the upper portions of the standards, means for actuating the slide, and a hoop-driving head at the bottom of and supported from and movable with the slide and having a substantially horizontal movement independent of the slide, said head, when it is at the required end of its independent movement in the upper position of the slide, being arranged to be lowered to

drive the head-hoop into place during the required descent of the slide, and the aforesaid standards having substantially vertical and parallel guideways engaged by the slide.

4. A machine of the character indicated comprising two laterally spaced standards between the lower portions of which is adapted to be mounted an open barrel onto the upper end of which a head-hoop is to be driven, a substantially vertically movable slide extending between the upper portions

of the standards, means for actuating said slide, and a hoop-driving head at the bottom of and supported from and movable with the slide and having a substantially horizontal movement independent of the slide 70 rearwardly from the forwardly toward the space between the standards, said head, when it is at the forward end of its independent movement in the upper position of the slide, being in position to be lowered 75 as required to drive the head-hoop into place during the required descent of the slide.

5. A machine of the character indicated comprising a base for supporting an upright 80 open barrel, a hoop-driving head, a non-rotatable and substantially vertically movable slide supporting said head and spaced upwardly from the barrel-receiving space over the aforesaid base, a substantially vertical screw threaded into the slide and held against endwise movement, and means for rotating the screw, the slide being arranged to be actuated downwardly or upwardly according as the screw is rotated in the 90 one or the other direction, and the aforesaid head being movable with the slide and having a movement independent of the slide and, when it is at the required end of its independent movement in the upper position 95 of the slide, being arranged to be lowered as required to drive a head-hoop into place during the required descent of the slide.

6. A machine of the character indicated comprising two laterally spaced standards 100 the lower portions of which are arranged at opposite sides respectively of the space for receiving an upright open barrel, a substantially vertically movable slide extending between the upper portions of the standards, a substantially horizontal track at the bottom of and extending rearwardly from under the forward portion of and rigid with the slide, means for actuating the slide, a hoop-driving head supported from and movable 110 endwise of said track, and means for limiting movement of said head endwise of the track, said head, when it is at the forward end of its movement endwise of said track in the upper position of the slide, being in 115 position to be lowered as required to drive a head-hoop into place during the required descent of the slide.

7. A machine of the character indicated comprising two laterally spaced standards, a 120 substantially vertically movable slide extending between the upper portions of the standards, means for actuating the slide, a track comprising two laterally spaced and substantially parallel bars which extend 125 rearwardly from under the forward portion of and which are rigid with the slide and have laterally projecting and substantially horizontal flanges spaced downwardly from the slide and extending endwise of 130

- said track, a hoop-driving head opposite the bottom of and spaced at its top downwardly from the slide and having rollers which are mounted on and movable endwise of said flanges, and means for limiting movement of said head endwise of the aforesaid track, said head, when it is at the forward end of its movement endwise of said track in the upper position of the slide, being in position to be lowered as required to drive a head-hoop into place during the required descent of the slide, the bottom of the slide being adapted to come into engagement with the top of said head after said head during said descent of the slide has come into engagement with the head-hoop to be driven into place, and the top of the rollers of said head being lower than the top of the head.
8. A machine of the character indicated comprising two laterally spaced standards, a substantially vertically movable slide extending between the upper portions of the standards, means for actuating the slide, a track comprising two laterally spaced and substantially parallel bars each of which extends rearwardly from under the forward portion of and is supported from the slide and has a laterally and inwardly projecting substantially horizontal flange spaced downwardly from the slide, a hoop-driving head opposite the bottom of and spaced at its top downwardly from the slide and movable endwise of and extending between said bars, and means for limiting movement of said head endwise of said track, said head being provided adjacent the aforesaid flange of each of said bars with a substantially horizontal roller resting on and arranged transversely of said flange and wholly below the top of said head, and said head, when it is at the forward end of its movement endwise of said track in the upper position of the slide, being arranged to be lowered as required to drive a head-hoop into place during the required descent of the slide.
9. A machine of the character indicated comprising two laterally spaced standards, a nonrotatable and substantially vertically movable slide extending between the standards, a substantially vertical screw threaded into the slide and long enough to extend through and below the slide in the lower position of the slide and held against endwise movement, means for rotating the screw, a track comprising two laterally spaced bars which are rigid with the slide and arranged at opposite sides respectively of the screw and having laterally projecting and substantially horizontal flanges extending rearwardly from under the forward portion of and spaced downwardly from the slide, a hoop-driving head extending between said bars and above said flanges and spaced at its top downwardly from the slide and provided adjacent each flange with a substantially hor-

izontal roller which is mounted on and arranged transversely of the flange and has its top lower than the top of said head, and means for limiting movement of said head endwise of the track, said head, when it is at the forward end of its movement endwise of the track in the upper position of the slide, being arranged to be lowered as required to drive a head-hoop into place during the required descent of the slide.

10. A machine of the character indicated comprising a base for supporting an upright open barrel onto the upper end of which a head-hoop is to be driven, a cable adapted to encircle the upper portion of the barrel preparatory to driving said hoop into place, a nonrotatable and substantially vertically movable slide spaced upwardly from said base, a substantially vertical screw threaded into said slide and held against endwise movement, means for rotating the screw, and a hoop-driving head supported from and movable with the slide and having a movement independent of the slide and in position to lower with the slide, or in an inoperative position, according as said head, in the upper position of the slide, is at the one or the other end of its independent movement, and means whereby the cable, upon placing it into its barrel-encircling position preparatory to the descent of the slide, is tightened in relation to the barrel during said descent of the slide and before said head comes into engagement with the hoop.

11. A machine of the character indicated comprising a base for supporting an upright open barrel, a cable for encircling the upper portion of the barrel, a hoop-driving head, a nonrotatable and substantially vertically movable slide supporting said head, a substantially vertical screw threaded into the slide and held against endwise movement, means for rotating said screw, two levers arranged adjacent the right-hand end and left-hand end respectively of the slide and operatively connected with opposite ends respectively of the cable, the aforesaid head being movable with the slide and having a movement independent of the slide and being in position to lower with the slide, or in an inoperative position, according as said head, in the upper position of the slide, is at the one or the other end of its independent movement, and means whereby the levers are actuated as required to tighten the barrel-encircling cable in relation to the barrel during the descent of the slide and before said head has come into engagement with the head-hoop to be driven into place.

12. A machine of the character indicated comprising a base for supporting an upright open barrel, a cable for encircling the barrel, a hoop-driving head, a nonrotatable and substantially vertically movable slide supporting said head, a substantially ver-

- tical screw threaded into the slide and held against endwise movement, means for rotating the screw, two upright levers adjacent the right-hand end and left-hand end respectively of the slide and pivoted at their lower ends and arranged to be swung from and toward each other and in their inner position in the upper position of the slide and operatively connected with opposite ends respectively of the cable, the aforesaid head being movable with the slide and having a movement independent of the slide and being arranged to be lowered to drive a hoop into place, or being in an inoperative position, according as said head, in the upper position of the slide, is at the one or the other end of its independent movement, and means whereby the levers are actuated outwardly as required to tighten the barrel-encircling cable in relation to the barrel during the descent of the slide and before said head has come into engagement with the hoop to be driven into place.
13. A machine of the character indicated comprising a base for supporting an upright open barrel, a cable for encircling the barrel, a hoop-driving head, a nonrotatable and substantially vertically movable slide supporting said head, a substantially vertical screw threaded into the slide and held against endwise movement, means for rotating the screw, and two levers adjacent the right-hand end and left-hand end respectively of the slide and pivoted at their lower ends and arranged to be swung from and toward each other and operatively connected with the cable and adapted during their outward movement to tighten the cable in relation to the barrel, and a coiled spring extending between the upper ends of and attached to the levers, the aforesaid head being movable with and independently of the slide and being inoperative, or arranged to be lowered to drive a hoop into place, according as said head, in the upper position of the slide, is at the one or the other end of its independent movement, and means whereby the levers are simultaneously actuated outwardly against the action of the aforesaid spring during the descent of the slide and before said head has come into engagement with the hoop to be driven into place.
14. A machine of the character indicated comprising a base for supporting an upright open barrel, a cable for encircling the barrel, a substantially vertically movable slide, means for actuating the slide, a hoop-driving head, two upright levers adjacent opposite ends respectively of the slide and pivoted at their lower ends and arranged to be swung from and toward each other, two bolts extending laterally of the machine and loosely through opposite levers respectively and attached to the cable, nuts thread-
- ed onto the bolts at the laterally outwardly facing sides of the levers, said levers being in their inner position in the upper position of the slide, and the aforesaid head being movable with and independently of the slide and being inoperative, or in position to lower with the slide, according as said head, in the upper position of the slide, is at the one or the other end of its independent movement, and means whereby the levers are actuated outwardly as required to tighten the barrel-encircling cable in relation to the barrel during the descent of the slide and before said head has come into engagement with the hoop to be driven into place.
15. A machine of the character indicated comprising a base for supporting an upright open barrel, a cable for encircling the barrel, a substantially vertically movable slide, means for actuating the slide, a hoop-driving head movable with the slide and adapted to drive a hoop into place during the descent of the slide, and two upright levers adjacent opposite ends respectively of the slide and pivoted at their lower ends and arranged to be swung from and toward each other, the levers being in their inner position in the upper position of the slide and operatively connected with opposite ends respectively of the cable, and said levers and the slide having means whereby the levers are actuated as required to tighten the barrel-encircling cable in relation to the barrel during the descent of the slide and before the aforesaid head has come into engagement with the hoop to be driven into place.
16. A machine of the character indicated comprising a base for supporting an upright open barrel, a cable for encircling the barrel, a substantially vertically movable slide, means for actuating the slide, a hoop-driving head movable with the slide and adapted to drive a hoop into place during the descent of the slide, and two levers adjacent opposite ends respectively of the slide and operatively connected with opposite ends respectively of the cable, each lever and the adjacent portion of the slide having the one an incline and the other a member which engages said incline, and said incline and incline-engaging member being relatively arranged as required to cause said lever to be actuated as required to tighten the barrel-encircling cable in relation to the barrel during the descent of the slide and before the aforesaid head has come into engagement with the hoop to be driven into place.
17. A machine of the character indicated comprising a base for supporting an upright open barrel, a cable for encircling the barrel, a substantially vertically movable slide, means for actuating the slide, a hoop-driving head movable with the slide and adapted to drive a hoop into place during the descent of the slide, and two upright levers adjacent

opposite ends respectively of the slide and pivoted at their lower ends and movable from and toward each other and operatively connected with the cable and in their inner position when the slide is in its upper position and adapted during their outward movement to tighten the barrel-encircling cable in relation to the barrel, the slide being provided adjacent each lever with a roller having its axis substantially parallel with the axis of the lever, and said lever having an upwardly and laterally inwardly facing incline which is engaged by said roller in the upper position of the slide and also having a laterally inwardly facing surface which extends downwardly from the lower end of said incline and is substantially vertical in the outer position of the lever and engageable by said roller in the lower position of the slide.

18. A machine of the character indicated comprising two laterally spaced standards, a cable for encircling a barrel, a substantially vertically movable slide, means for actuating the slide, a hoop-driving head movable with the slide and adapted to drive a hoop into place during the descent of the slide, two upright levers at the rear of oppo-

site standards respectively and pivoted at their lower ends and movable from and toward each other and connected to the cable and in their inner position when the slide is in its upper position and adapted during and before completing their outward movement to tighten the barrel-encircling cable in relation to the barrel, and a coiled spring extending between and attached to the levers, the slide being provided adjacent each lever with a roller, said lever having an upwardly and laterally inwardly facing incline which is engaged by said roller in the upper position of the slide and also having a laterally inwardly facing surface which extends downwardly from the lower end of said incline and is substantially vertical in the outer position of the lever, and each lever having a member extending opposite the laterally inwardly facing side of the adjacent standard and arranged to cooperate with said standard in forming a stop for limiting outward movement of the lever.

In testimony whereof, I sign the foregoing specification, this 22nd day of November, 1921.

WILLIAM CLARK.
